DESIGN FOR A SHAKER FOR SALT OR PEPPER

Hamilton O. Cornwall, Pelham Manor, N. Y.

Application March 4, 1940, Serial No. 90,665

Term of patent 3½ years

To all whom it may concern:

Be it known that I, Hamilton O. Cornwall, a citizen of the United States and residing at Pelham Manor, in the county of Westchester and State of New York, have invented a new, original, and ornamental Design for a Shaker for Salt or Pepper, of which the following is a specification, reference being had to the accompanying drawing, forming part thereof, and in which

Fig. 1 is a top plan view of a shaker for salt or pepper, showing my design; and

Fig. 2 is a front elevational view thereof.

I claim:

The ornamental design for a shaker for salt or pepper, substantially as shown.

HAMILTON O. CORNWALL.
